UNITED STATES PATENT OFFICE.

JOHN HARRIS, HENRY W. GAZELL, AND LORENZ H. VOGEL, OF CLEVELAND,
OHIO.

ACETYLENE-GAS GENERATOR

SPECIFICATION forming part of Letters Patent No. 628,462, dated July 11, 1899.
Application filed November 28, 1898. Serial No. 697,683. (No model.)

To all whom it may concern:

Be it known that we, JOHN HARRIS, HENRY W. GAZELL, and LORENZ H. VOGEL, citizens of the United States, residing at Cleveland, in the county of Cuyahoga and State of Ohio, have invented a new and useful Acetylene-Gas Generator, of which the following is a specification.

Our invention relates to apparatus for the generation of acetylene gas; and the chief object in view is to provide an improved means for regulating the admission of water to the generator, to the end that a limited quantity of water may be admitted for attacking the carbid and secure the generation of gas while the carbid is in an active state; but the water-supply will be entirely cut off on the exhaustion of the carbid, thus leaving the calcium residue in a moistened condition and free from saturation by the water, whereby the spent carbid is not flooded by continued increments of water and the generator may readily be cleansed from the spent carbid preliminary to placing a fresh charge of active carbid in said generator.

A further object of the invention is to provide means by which the gas is cooled and condensed as it passes to the gasometer, and the water of condensation from the gas is discharged into a trapped condenser-chamber, and in our apparatus the gas-conveying pipe and the vent-pipe of the gasometer are supported by a single trap, which is situated centrally within the gasometer.

With these ends in view our invention consists in the novel combination of elements and in the construction and arrangement of parts, which will be hereinafter fully described and claimed.

To enable others to understand the invention, we have illustrated a preferred embodiment thereof in the accompanying drawings, forming a part of this specification, and in which—

Figure 1 is a sectional elevation through a gasometer and a generator of an apparatus constructed in accordance with our improvements. Fig. 2 is a vertical sectional elevation on the plane at right angles to Fig. 1 and indicated by the dotted line 2-2 of said figure.

Fig. 3 is a detail perspective view of the rocking arm and the tiltable vessel detached from the gasometer. Fig. 4 is a vertical sectional view through the arm and the valve which is controlled thereby. Fig. 5 is a detail section on a plane at right angles to Fig. 4 and indicated by the dotted line 5-5. Fig. 6 is an enlarged view of the head of the generator, illustrating the sprayer.

Like numerals of reference denote like and corresponding parts in each of the several figures of the drawings.

The gasometer which is employed in our apparatus is similar in its general aspect to ordinary gas-receivers familiar to those skilled in the art. The tank 10 of the gasometer has a raised bottom 11, and within the liquid contents of the tank is immersed the inverted floatable bell 12. This bell carries a slidable vent-tube 13, which is fastened securely to the head of the bell and is arranged centrally thereon, and this slidable vent-tube is provided with one or more transverse perforations 14 near its lower end, so that the perforations in the normal working position of the bell are immersed in and sealed by the liquid contents of the tank. A trap-shell 15, preferably of conico-cylindrical form, is arranged partly within the tank and partly below the bottom 11 thereof, and this trap-shell is united securely at a point intermediate of its length to the bottom 11, so that its upper end protrudes into the tank for the reception of the vent-pipe 16. This vent-pipe has a vertical length or section which extends centrally through the tank 10 to a point above the level of the liquid contents of the tank, and the vent-tube 13 is telescopically fitted over the vent-pipe 16 to normally cut off the escape of gas through the automatic vent appliances of the apparatus. The tubes or pipes 13-16 are disposed vertically and centrally within the gasometer to serve as a guide for the floatable bell in its vertical travel within the tank, and in the event of excessive generation of gas the floatable bell is raised to a point where the perforation 14 in the telescopic tube 13 is lifted above the water-level in the tank, thus providing for the outlet of a certain quantity of gas. The lower end of the vent-pipe 16 is sealed.

cured firmly in the upper contracted end of the conical trap-shell 15, and said end of the vent-pipe 16 is provided with an elbow 17, which is carried through one side of the trap-
5 shell 15 for union with a horizontal branch-pipe 18, which is conducted through the tank 10 above the bottom 11 thereof and below the lowest point in the travel of the floatable bell 12. A vent-pipe may be connected with the
10 protruding end of the branch 18 to lead the escaping gas outside of a dwelling or building in which the apparatus may be installed.

The trap-shell 15 is designed to contain a limited quantity of water to form a seal 19 therein, and with this drip-chamber communicates a condensing coil or worm 20 and the connecting-pipe 23, that conveys the gas from the generator to the gasometer. The condensing coil or worm 20 is erected in a vertical position within the tank 10 for submersion in the liquid contents thereof, and the upper extremity of this condensing-coil is extended above the level of the water within said tank for the purpose of discharging the
25 gas after it shall have been cooled and condensed into the floatable bell of the gasometer. The condensing-coil has its lower portion formed into an angular length 21, which is carried through the upper part of the trap-
30 shell 15, which projects into the tank 10, and this angular length of said coil terminates in a vertical foot 21^a, which dips into or is immersed in the seal 19 of the trap-shell. This dip-foot of the condensing-coil is provided at
35 a point above the liquid seal 19 in the trap with a T connection 22, to which is united the gas-pipe 23. The dip-foot and its T connection are arranged in a horizontal plane below the bottom 11 of the tank, and the gas-
40 pipe 23 may thus be carried through the lower portion of the tank 10 below the bottom 11 thereof. The gas from the generator is conducted by the pipe 23 to the condensing-coil 20, through which the gas circulates as it
45 passes to the floatable bell, and this coil being submerged in the cool water of the tank the aqueous vapors in the gas are condensed by the gas impinging against the cooled coil. The water of condensation is discharged from
50 the coil through the angular length and the dip-foot thereof into the seal of the trap-shell; but the gas is prevented from escaping through the foot 21^a and into the trap-shell, because said foot is immersed in the liquid seal 19.
55 The seal is augmented by the discharge of the water of condensation from the gas, and the accumulated liquid in the trap-shell 15 is permitted to overflow into a discharge-pipe 24, which is attached to the trap-shell 15 at
60 the desired level of the liquid seal 19 therein. This overflow-pipe 24 lies below the bottom of the tank 10 and extends through the shell of said tank to discharge into a suitable vessel.

65 The generator of our apparatus is situated externally to the gasometer, and said generator has a shell or vessel 25 of conico-cylindrical

form. The bottom of the generator is closed by an imperforate head; but the open upper end of the generator-shell has a cast-metal ring-like head 26 united thereto in a manner to secure a gas-tight joint between said conical shell and the cast-metal head. This head 26 is cast in a single piece of metal, with a recessed seat 27 and short standards 75 28. The seat 27 is concentric with an opening in the head, and said seat receives a compressible gasket 29, upon which is placed the cover 30, which is held firmly on the gasket by a clamping-screw 31, having a threaded bearing in a cross-bar 32, supported by the standard 28. The employment of the tapered generator vessel is advantageous, because the cross-sectional area of the upper portion of the vessel is less than the area of the lower closed end thereof, and this form of the vessel enables a comparatively small cover 30 to be employed, which may be fastened or clamped securely in place by a single screw.

For the purpose of supplying water to the generator we employ a trapped water-pipe 33, which is erected in vertical position alongside the generator and contiguous to the gasometer-tank, and one leg of this trapped water-pipe has an elbow 34, which is connected to the head or cover of the generator, so as to communicate with a sprayer 35, situated within the generator, immediately below the cover 30 thereof. The other leg of the trapped water-pipe has an enlarged funnel-shaped mouth 36, which is open for the free ingress of water from a tilttable réceptacle, which will be presently described. The employment of the trapped water-pipe connected with the generator enables a column of water to be maintained in active relation to the generator for the prevention of the escape of gas therefrom through the water-supply devices, and the funnel-shaped mouth 36 of this trapped water-pipe is in a horizontal plane above the delivery end of said trapped pipe, so that an increase in the supply of water contained within the trapped pipe will overflow into the sprayer 35. This sprayer consists of the connected annular tubes 37 38, arranged substantially concentric one with the other and in the same horizontal plane, and the tubes are operatively connected by the cross-tube 39. The elbow 34 of the water-pipe 33 is attached, preferably, to the outer sprayer-tube 37, and the water from the pipe 33 flows through the tubes 37 38 in order to insure an equal distribution of the water over the charge of carbid within the generator-shell. We preferably provide the inner sprayer-tube 38 with a series of orifices 40, while the outer sprayer-tube 37 has a series of jet-nipples 41, which diverge in a downward direction and deliver the water in thin streams upon the charge of carbid adjacent to the conical shell of the generator. The gas-pipe 23 is bent in an upward direction alongside the generator, and its upper end is formed into an elbow 42, which is attached to the

head or cover of said generator for the purpose of conveying the gas from the generator to the condenser-coil within the gasometer.

In our apparatus we employ a water-feed mechanism which takes or receives its supply of water from the contents of the gasometer-tank and which is controlled in a positive and automatic manner by the vertical travel of the floatable bell, and this water-feed mechanism has combined therewith a valve or cut-off, which on the exhaustion of the carbid within the generator serves to completely shut off the supply of water to the water-feed mechanism, and thereby prevent the continued ingress of water to the generator, whereby the spent calcium residue in said generator is left in a moistened condition as distinguished from a flooded, saturated, and pasty mass. The water-feed mechanism embraces a bracket-plate 43, a hollow swinging arm 44, a tilttable receptacle 45, which is carried by the arm to travel therewith and is in operative relation to the funnel-mouth of the trap-pipe 33, and a cam-rod 46, movable with the gasometer-bell and operatively connected with the swinging hollow arm, so as to depress the latter from a vertical position to a horizontal position on the descent of the gas-bell and to restore said arm to a vertical position when the floatable bell is raised by accumulation of gas therein. The cam-rod 46 is slidably fitted within a loop-shaped guide 47, which extends outwardly from the swinging hollow arm 44 at a point intermediate of the length thereof, and said guide is equipped with a clamping-plate 48, which is secured firmly on the arm 44 in any approved way. The vertical cam-rod 46 is secured at its upper end to the floatable bell in a suitable manner, and at a point intermediate its length this rod is formed with a crook or offset 49, which is adapted to ride against the guide 47 in a manner to raise or lower the hollow arm 44 positively on the vertical travel of the floatable bell. The swinging arm 44 is preferably tubular throughout its length, although it may be any other desired shape in cross-section, and with this tubular arm communicates the discharge-nozzle 50, which extends substantially at right angles to the length of the arm and is attached thereto at or near its outer extremity. The outer open end of the hollow swinging arm is closed by means of a plug 51, that protrudes beyond said extremity of the arm, and in the protruding end of this plug is a transverse eye 52, which receives the hanger-bail 53 of the tilttable receptacle 45. This hanger-bail is held firmly at an angle to the axis of the swinging arm by a clamping-screw 54, which finds a threaded opening in the plug 51 and impinges against the bail 53, and this bail is pivotally connected at its lower end to the receptacle 45 by means of the hinge-rod 55, said rod passing through suitable ears on the receptacles 45 and through the ends of the hanger-bail. The tilttable receptacle 45 has an inclined or slop-

ing bottom, and said receptacle tapers in the direction of its length. The receptacle is hung or pivoted on the bail eccentrically in 70 order that it may balance itself and assume normally a horizontal position. The swinging arm 44, which carries the tilttable receptacle 45, is maintained in a vertical position by the cam-rod 46, which travels with the 75 floatable bell, and by clamping the hanger-bail 53 at an angle to the axis of the swinging arm this tilttable receptacle is supported in a position to one side of the discharge-nozzle 50 when the arm 44 is in its normal vertical position. The position of the swinging arm and the tilttable receptacle when the gas-bell is in its raised active position is indicated by Fig. 2 of the drawings; but when the volume of gas in the floatable bell is reduced by consumption at the burners the bell descends and with it the cam-rod 46. The crook or offset 49 in the cam-rod travels through the loop-shaped guide 47 to lower the swinging arm from a vertical position to a substantially 90 horizontal position, and as the arm travels in an arc and as the tilttable receptacle is pivotally suspended from the arm the nozzle 56 assumes a position over the heel of the tilttable receptacle, so as to discharge the water 95 from the arm 44 into the tilttable receptacle. This receptacle is normally supplied with a limited quantity of water, and the increase in the volume of water within the tilttable receptacle by the water flowing from the nozzle 100 of the hollow arm overbalances the tilttable receptacle and causes it to empty a limited volume of water into the mouth 36 of the trapped water-pipe 33. It is designed to arrange the valve 56 and the pivotal support of 105 the arm on the gasometer-tank at such a point relatively to the water-level in the tank that the water will not flow from the hollow arm and the nozzle 50 thereof until that arm assumes a substantially horizontal position, and 110 by providing the tilttable bucket between the delivery end of the arm and the mouth of the trapped water-pipe the volume of water delivered to the trap-pipe may be regulated to a nicety. As the water is supplied to the 115 trapped pipe it flows to the sprayer and is distributed by the latter over the charge of carbid in the generator. The gas is generated by the water attacking the carbid, and it flows through the pipe 23 and the condensing-coil to the floatable bell. Said bell is raised by accumulation of gas therein, and as the bell ascends the cam-rod 46 travels with it and raises the hollow arm 44 to its normal upright position, thereby cutting off the flow 125 of water to the generator.

In order to entirely cut off the flow of water from the gasometer to the generator when the charge of carbid is spent or exhausted within the generator, we provide a valve 56, 130 which is actively combined with the bracket-plate 43 and the swinging arm 44 to close the communication between the gasometer-tank and the arm when the latter is carried by the

bell to a position below the horizontal plane in which the arm delivers water to the tilt-able receptacle. In the preferred embodiment of the cut-off mechanism the valve remains open during the travel of the arm 44 from a vertical to a horizontal position, and vice versa, and this cut-off valve is brought into service only when the carbid is exhausted and the bell descends below the position where it normally actuates the valve to admit water to the generator. The cut-off or valve is in the form of a conical plug 56, which is provided with a longitudinal passage 57, that communicates with a bushing or nipple 58, which is attached by the bracket-plate 43 to the gasometer-tank on a plane below the level of the liquid contents of said tank 10, and the conical valve is thus in communication with the gasometer-tank to supply water thereto from the swinging arm 44. The plug of the valve is provided with a transverse port 60, which is in communication with the longitudinal passage through the plug, and on this conical plug is fitted a valve-shell 59, which is attached firmly to the inner end of the rocking arm 44 and serves to pivotally connect said arm to the valve-plug 56. This valve-shell has a port 61, which communicates at all times with the longitudinal passage in the hollow arm, and an arc-shaped passage 62 is provided in the plug 56 or the valve-shell 59 to establish communication between the ports 60 and 61 during the travel of the arm 44 from its vertical to its horizontal position. The length of this passage is such that the arm 44 communicates freely through the valve-plug with the gasometer-tank at all points in the adjustment of the arm within an arc of ninety degrees; but when the gas-bell and the cam-rod descend below the limit of travel in the active condition of the bell the shell 59 is turned by the arm to a position where the passage 62 and the port 61 of the shell are moved out of communication with the port 60 in the valve-plug, thereby entirely cutting off communication from the arm 44 and the gasometer-tank. The employment of the automatic valve between the rocking arm and the gasometer-tank prevents the ingress of such a large volume of water as is requisite to effect flooding of the carbid, and the calcium residue is left in a moistened condition as distinguished from a pasty mass, whereby the generator when detached may be readily cleaned of the exhausted charge and supplied with a fresh active charge of carbid.

The shell 59 of the automatic cut-off is held on the conical plug by a washer 63 and a screw 64 to prevent disconnection of the parts and enable the conical plug and shell to be united together in a manner to overcome leakage of gas. While we prefer to employ an automatic valve of the class described, which remains open between the limits of the play of the rocking arm within a prescribed arc, we do not desire to strictly confine ourselves to the

precise construction of the valve herein shown and described.

The service-pipe 65 has a vertical branch 70 which is extended or carried through the gasometer-tank to communicate with the chamber of the gas-bell, and to the protruding end of this pipe is attached a cock or valve 66, which may also serve as the means for uniting the burner-pipe to the apparatus.

Changes may be made in the form and proportion of some of the parts, while their essential features are retained and the spirit of the invention embodied. Hence we do not desire to be limited to the precise form of all the parts as shown, reserving the right to vary therefrom.

Having thus described the invention, what we claim is—

1. In an acetylene-gas apparatus, the combination with a generator, of a trapped water-pipe communicating with the generator, a floatable gas-bell, a rocking arm communicating with a source of water-supply, a vessel carried by said arm and arranged to deliver its contents to said trapped pipe, and means for operatively connecting the rocking arm with the floatable bell, substantially as described.

2. In an acetylene-gas apparatus, the combination with a generator and a gasometer having a floatable bell, of a trapped pipe connected with the generator, a rocking arm mounted on the gasometer to communicate therewith, a cam connected with the rocking arm and movable with the floatable bell to positively actuate said arm, and a tilttable vessel carried by the rocking arm and arranged to receive water therefrom, said vessel adapted, when overbalanced, to deliver its contents to the trapped pipe, substantially as described.

3. In an acetylene-gas apparatus, the combination with a generator and a gasometer, of a rocking arm, connections between said arm and the floatable bell of the gasometer, a valve which remains open during the play of the arm within certain limits and is closed when the arm assumes an abnormal position, and means to deliver water in limited quantities from the rocking arm to the generator, substantially as described.

4. In an acetylene-gas apparatus, the combination with a generator and a gasometer, of a rocking arm, a cut-off or a valve serving as the pivot for the rocking arm and establishing communication between said arm and the gasometer within certain limits of the play of the arm, a tilttable vessel carried by said arm, a trapped water-pipe connected with the generator and arranged to receive from the tilttable vessel, and means between the gas-bell and the arm to positively actuate the latter, substantially as described.

5. In an acetylene-gas apparatus, the combination with a gasometer and a generator, of a rocking arm pivotally mounted on the gasometer to receive its supply of water there-

from, a cam-rod attached to the gasometer-bell and slidably connected to the rocking arm, a tiltable vessel mounted on said arm to travel therewith, and a pipe in active relation to said tiltable vessel and connected with the generator, substantially as described.

6. In an acetylene-gas apparatus, the combination of a rocking arm mounted pivotally for communication with a source of water-supply and provided at or near its outer end with a delivery-nozzle, a hanger-bail arranged at an angle to the arm and attached thereto, a tiltable receptacle pivoted on said bail, a generator, and an inlet-pipe arranged to receive from the receptacle and to deliver to the generator, substantially as described.

7. In an acetylene-gas apparatus, the combination of a source of water-supply, a generator, a rocking feed device communicating with said source of supply, a valve controlled by the rocking feed device to remain open within the limits of the play of the rocking feed device in its normal position and to be closed automatically when said rocking feed device assumes an abnormal position, a generator, and a trapped pipe connected with the generator and arranged to receive from the rocking feed device, substantially as described.

8. In an acetylene-gas apparatus, the combination with a gasometer, of a valve connected thereto and having a rocking arm mounted thereon for communication with said gasometer in the normal position of said arm, a generator, means connected with the

gas-bell to control the position of the arm, and a tiltable receptacle carried by the arm and arranged to deliver to the generator, substantially as described.

9. In a gas-generator, the combination with a gas-bell, a generator, and a source of water-supply, of a trapped pipe leading to said generator, a rocking feed device operative with the gas-bell and connected with the source of water-supply to deliver water to said trapped pipe, and a valve controlled by the rocking play of the feed device to regulate the flow of water to the trapped pipe, substantially as described.

10. In an acetylene-gas apparatus, a sprayer consisting of the concentric connected tubes, one of which is provided with diverging discharge-nipples and the other tube having orifices, in combination with a generator within which the sprayer is suspended, a water-pipe connected with the sprayer, a gas-pipe, a gasometer, and a feed mechanism to the water-pipe, substantially as described.

In testimony that we claim the foregoing as our own we have hereto affixed our signatures in the presence of witnesses.
